UNITED STATES PATENT OFFICE.

ALLEN B. CURETON, OF PUEBLO, COLORADO, ASSIGNOR TO PUEBLO WIRE STRETCHER MANUFACTURING COMPANY, OF PUEBLO, COLORADO, A CORPORATION OF COLORADO.

PULLING IMPLEMENT.

1,289,403.

Specification of Letters Patent. Patented Dec. 31, 1918.

Application filed February 12, 1917. Serial No. 148,114.

To all whom it may concern:

Be it known that I, ALLEN B. CURETON, a citizen of the United States, residing at Pueblo, in the county of Pueblo and State of Colorado, have invented certain new and useful Improvements in Pulling Implements, of which the following is a specification, reference being had to the accompanying drawings.

10 This invention relates to certain improvements in pulling implements and has relation more particularly to a device of this general character especially designed and adapted for use in connection with wire and 15 the like; and it is an object of the invention to provide a pulling implement having novel and improved means whereby a substantial direct pull may be obtained and which includes a flexible winding member which is 20 positioned free from contact with the operating means.

The invention also has for an object to provide a device of this general character including a driven shaft with which a flexible 25 tape or the like is directly connected and which tape is adapted to be engaged with the wire or other object to be pulled and whereby the driven shaft may be caused to rotate by a single operator.

30 The invention consists in the details of construction and in the combination and arrangement of the several parts of my improved pulling implement whereby certain important advantages are attained and the 35 device is rendered simpler, less expensive and otherwise more convenient and advantageous for use, all as will be hereinafter more fully set forth.

The novel features of the invention will 40 hereinafter be definitely claimed.

In order that my invention may be the better understood, I will now proceed to describe the same with reference to the accompanying drawings, wherein—

45 Figure 1 is a view in top plan of a pulling implement constructed in accordance with an embodiment of my invention with certain of the parts in fragment; and

50 Fig. 2 is a longitudinal vertical sectional view taken through the device as disclosed in Fig. 1 with certain of the parts omitted.

As disclosed in the accompanying drawings, 1—1 denotes two parallel plates main-

tained in predetermined spaced relation through the medium of the interposed sleeves 2 surrounding the holding members 3. The holding members 3 as herein embodied constitute conventional bolts and nuts and are positioned adjacent the opposite ends of the plates 1, and one of said bolts extends beyond the outer faces of the plate 1 and has pivotally engaged with its extended portions the gravity pawls 4 for a purpose to be hereinafter more particularly referred to.

65 Substantially midway of the plates 1 is rotatably mounted the shaft 5 which bridges the space between the plates 1 and extends beyond the outer faces thereof. Fixed to the extended portions of the shaft 1 are the 70 gears 6 of equal diameter and with which coact the gravity pawls 4 hereinbefore referred to for holding said gears 6 against movement in one direction or against movement under the influence of the strain imposed upon the tape T operatively engaged with the shaft 5.

75 The portions of the plates 1 provided with the pawls 4 constitute the rear part of my improved implement or machine and suitably affixed to the rear portion of one of the plates 1 is the flexible member F herein disclosed as a link chain which is adapted to be detachably engaged with a hook member 7 suitably anchored to the rear portion 80 of the second plate 1 and with which the member F is adapted to be detachably engaged so that my improved implement or machine may be suitably anchored in applied position as to a fence post or other 85 stationary member.

90 Rotatably supported by the plates 1 in advance of the gears 6 is the shaft 8 which also extends beyond the outer face of the plates 1. Fixed to the extended portions of the shaft 8 are the pinions 9 in mesh with the gears 6. It is preferred that the gears 6 and the pinions 9 be of a ratio of 4 to 1, although I do not wish to be understood as 95 limiting myself to this exact proportion.

100 Also operatively engaged with an extended portion of the shaft 8 is an operating handle or crank 10 whereby it will be at once self-evident that the shaft 5 may be 105 suitably driven by a single operator.

The tape T hereinbefore referred to is

preferably formed of sheet steel and is of any desired length and also of a width substantially equal to the space between the plates 1. The tape T extends forwardly of 5 the implement or machine and between the sleeves 2 and below the shaft 8. The outer or free end of the tape T is returned, as at 11, to afford a barrel through which is disposed the holding bolt 12 also directed 10 through the free ends of the yoke member 14. The yoke member 14 is of such width as to have its free ends contact with the forward ends of the plates 1 in order to 15 limit the winding of the tape T above the shaft 5.

In swiveled engagement with the yoke member 14 is the hook 15 which provides means whereby the tape T may be engaged with a wire clamp or directly with the object to be pulled. As the character of wire 20 clamp or other attaching means coacting with the hook 15 forms no part of my present invention, it is not thought that a detail 25 description or illustration thereof is necessary.

From the foregoing description, it is thought to be obvious that a pulling implement constructed in accordance with my invention is of an extremely simple and comparatively inexpensive nature and is particularly well adapted for use by reason of the convenience and facility with which it may be assembled, and it will also be obvious 30 that my invention is susceptible of some change and modification without material departure from the principles and spirit thereof and for this reason I do not wish to be understood as limiting myself to the 35 precise arrangement and formation of the several parts herein shown in carrying out 40

my invention in practice, except as herein-after claimed.

I claim:

A device of the character described comprising two spaced parallel plates, bolts 45 connecting said plates, sleeves surrounding the bolts and positioned between the plates for maintaining the plates in spaced relation, one of said bolts extending beyond the plates, gravity pawls pivotally engaged with 50 the extended portion of said bolt, two longitudinally spaced shafts rotatably supported by the plate and extending therebeyond, gear wheels fixed to the extended portions of one of the shafts and with which the 55 gravity pawls co-act to hold said gear wheels against retrograde movement, pinions carried by the extended portions of the second shaft and in mesh with the gears, a crank co-acting with the extended portion of the 60 second shaft, a tape having one end portion secured to the second shaft intermediate the plates and adapted to be wound about said second shaft, the bolts connecting the plates through the end portions thereof adjacent 65 said second shaft being transversely spaced, said tape extending between such bolts, said tape being of a width substantially equal to the space between the plates, engaging means carried by the outer end portion of the tape, and anchoring means co-acting with the end portions of the plate remote 70 from the second shaft.

In testimony whereof I hereunto affix my signature in the presence of two witnesses.

ALLEN B. CURETON.
